DESIGN FOR AN ANDIRON

William E. Atkinson, Montague, Mich., assignor
to Valley Research Corporation, Montague,
Mich., a corporation of Michigan

Application November 1, 1946, Serial No. 134,449

Term of patent 14 years

(Cl. D81—6)

To all whom it may concern:

Be it known that I, William E. Atkinson, a citizen of the United States of America, residing at Montague, in the county of Muskegon, State of Michigan, have invented a new, original, and ornamental Design for Andirons, of which the following is a specification, reference being had to the accompanying drawing, forming part thereof, in which:

Fig. 1 is a side view slightly in perspective of an andiron embodying my new design; and

Fig. 2 is a similar view from the front thereof.

I claim:

The ornamental design for an andiron, as shown.

WILLIAM E. ATKINSON.
